(57) **CLAIM**

The ornamental design for a griddle as shown and described.

DESCRIPTION

FIG. 1 is a perspective view of the griddle of our design; FIG. 2 is a bottom plan view of the griddle of FIG. 1; FIG. 3 is a top plan view of the griddle of FIG. 1; FIG. 4 is a front elevation of the griddle of FIG. 1; FIG. 5 is a rear elevation of the griddle of FIG. 1; FIG. 6 is a right side elevation of the griddle of FIG. 1; and, FIG. 7 is a left side elevation of the griddle of FIG. 1. Features shown in broken lines are for illustrative purposes only and form no part of the claimed design. Lighter solid lines denote surfaces and contours. Line shading is not surface ornamentation.
